UNITED STATES PATENT OFFICE.

FRED L. MILLS, OF OAK PARK, ILLINOIS, ASSIGNOR TO MILLS NOVELTY COMPANY, OF CHICAGO, ILLINOIS, A CORPORATION OF ILLINOIS.

DESIGN FOR A FORTUNE-TELLING-MACHINE CASING.

Application filed December 30, 1926. Serial No. 20 239. Term of patent 14 years.

To all whom it may concern:

Be it known that I, FRED L. MILLS, a citizen of the United States, residing at Oak Park, in the county of Cook and State of Illinois, have invented a new, original, and ornamental Design for Fortune-Telling-Machine Casing, of which the following is a specification, reference being had to the accompanying drawing, forming a part thereof.

On the drawing,

I claim:

The ornamental design for a fortune-telling machine casing, as shown.

FRED L. MILLS.
